McCormick

[11] Patent Number: Des. 423,191

[45] Date of Patent: ** Apr. 25, 2000

[54] FRAYABLE PANTS LEGS

5,513,392 5/1996 Douglas et al. 2/207

[75] Inventor: James Patrick McCormick,
Englewood Cliffs, N.J.Primary Examiner—Celia Murphy
Attorney, Agent, or Firm—Ostrager Chong Flaherty &
Onofrio, P.C.[73] Assignee: Generation X International Corp.,
New York, N.Y.

[57] CLAIM

[**] Term: 14 Years

I claim the ornamental design for frayable pants legs, as
shown and described.

[21] Appl. No.: 29/094,030

DESCRIPTION

[22] Filed: Sep. 24, 1998

FIG. 1 for convenience of illustration is an enlarged fragmentary view of frayable pants legs of FIG. 2 showing my new design;

[51] LOC (6) Cl. 02-02

FIG. 2 is a front elevational view of frayable pants legs showing my new design, the rear being a mirror image thereof;

[52] U.S. Cl. D2/742

FIG. 3 is a front elevational view of an alternate embodiment of the design shown in FIG. 2;

[58] Field of Search D2/823, 742; 2/227,
2/232, 74, 92, 88, 244, 207; 139/396

FIG. 4 is a right side elevational view of FIG. 3;

[56] References Cited

FIG. 5 is a top plan view of FIG. 3;

U.S. PATENT DOCUMENTS

FIG. 6 is a bottom plan view of FIG. 3;
